DESIGN FOR A CONTAINER FOR COSMETICS

Morris Walhimer, New Haven, Conn.

Application December 30, 1944, Serial No. 117,161

Term of patent 3½ years

(Cl. D58—11)

To all whom it may concern:

Be it known that I, Morris Walhimer, a citizen of the United States, residing at New Haven, in the county of New Haven and State of Connecticut, have invented a new, original, and ornamental Design for a Container for Cosmetics, of which the following is a specification, reference being had to the accompanying drawing, forming a part thereof.

In the drawing:

The figure is a perspective view of a container for cosmetics, showing my new design.

The opposite side of the container for cosmetics is identical to that shown and the opposite end is plain and unornamented.

I claim:

The ornamental design for a container for cosmetics, as shown and described.

MORRIS WALHIMER.
